Inventor
William F. Delaney
By his Attorney, J. R. Little,

UNITED STATES PATENT OFFICE.

WILLIAM E. DELANCY, OF ADAMS, MASSACHUSETTS.

AUTOMATIC AIR-BRAKE.

SPECIFICATION forming part of Letters Patent No. 772,702, dated October 18, 1904.

Application filed February 5, 1904. Serial No. 192,134. (No model.)

To all whom it may concern:

Be it known that I, WILLIAM E. DELANCY, a citizen of the United States, and a resident of Adams, in the county of Berkshire and State of Massachusetts, have invented certain new and useful Improvements in Automatic Air-Brakes, of which the following is a specification.

My invention relates to air-brakes.

10 It has for its object to provide an air-brake constructed and arranged to be mounted on a car or other vehicle and be manually controlled by the motorman or brakeman and means for automatically regulating the air-pressure in the compressed-air-storage cylinder for operating the brakes.

15 It has for a further object to provide a device of the character set forth embodying advantages in point of perfect operation, simplicity, general utility, and inexpensiveness.

20 In the drawings, Figure 1 is a top plan view of my air-brake, the bottom of the car to which it is attached being indicated in dotted lines. Fig. 2 is a horizontal sectional view taken through the several cylinders. Fig. 3 is a detail view showing the suspended gear-wheel in engagement with the axle-gear in full lines and out of engagement therewith in dotted lines. Fig. 4 is a fragmentary view 25 showing the means for guiding the frame 3.

30 Corresponding parts in all the figures are denoted by the same reference characters.

Referring to the drawings, in which for the purpose of illustration I have shown my 35 brake applied to a car, 1 designates a crank-axle journaled in the lower forked ends of a centrally-pivoted foldable arm 2, the upper end of which is pivotally connected to a frame 3, vertically slidable on guides 3^a, secured to 40 the bottom of the car directly over one of the axles, and the lower ends of the frame having holes through which the car-axle extends and in which it revolves, and said crank-axle has a gear-wheel 4 thereon between the 45 forked ends of the arm 2 and adapted to be thrown into and out of engagement with a gear-wheel 5 on the car-axle, whereby the crank-axle is rotated or its rotation stopped, as the case may be.

50 One end of a rod 6 is connected to the pivot

of the arm 2, and its other end has a sliding joint connection at 4^a with one end of a short arm 7, to be described, the other end of the short arm being pivotally connected to one end of a lever 8, pivoted at 9 on the bottom 55 of the car, said lever being pivotally connected at its ends to brake-rods 10 and 11, pivotally connected to the pivoted levers 12 and 13, respectively, for operating the front and rear brake-beams 14 14^a and 15 15^a, respectively. The sliding joint connection 4^a comprises a cylinder 4^b, having flanges 4^c at each end, a hole 4^d extending through it, and a collar 4^e is loosely mounted upon and adapted to slide on said cylinder between the 65 flanges 4^c. The rod 6 is fixed in the hole 4^d at one end of the cylinder, and the short arm 7 slides into the hole 4^d at the opposite end of the cylinder.

A compressed-air-storage cylinder 14^b is 70 supported on the bottom of the car between the front and rear axles and on one side communicates with two air-compression cylinders 16 and 17 for compressing air therein, the piston-rods 18 and 19 on said compression-cylinders being connected to the cranks 20 and 21, respectively, of the axle 1, whereby they are reciprocated in their cylinder.

75 For the purpose of turning the lever 8 on its pivot, and thereby operating the brake-beams 80 to contact with the car-wheels through the medium of the brake-rods 10 and 11, a pipe 22 runs out of one end of the compressed-air-storage cylinder 14^b and into one end of a compression-cylinder 23, and the piston-rod 24 of 85 said cylinder 23 projects out of the opposite end and is pivotally connected with said lever 8.

80 For the purpose of placing the feeding of compressed air to said cylinder 23 under the 90 control of the motorman or brakeman a valve 42 is located in the pipe 22.

95 For the purpose of automatically controlling the air-pressure in the compressed-air-storage cylinder a regulating-cylinder 25 communicates at one end with the opposite side of the compressed-air-storage cylinder 14^b to that of the air-compression cylinders, and the piston-rod 26 of said cylinder 24 projects through its outer end, the inner end of said 100

piston-rod 25 having a coil-spring 27 thereon for holding it and its piston normally in their inner position, as shown in dotted lines in Fig. 2, and the outer end of the piston-rod is pivotally connected to one end of a lever 28, pivoted at 29 on the bottom of the car, and the other end of the lever 28 is pivotally connected by a link 30 with one end of a lever 31, pivoted at 32 on the bottom of the car and having its other end connected to the collar 4°, whereby when the piston-rod 26 is being forced outwardly by its piston into the position shown in full lines in Fig. 2 the rod 6 will pull the arm 2 and the cog-wheel 4 into the position shown in dotted lines in Fig. 3, thereby stopping the compression of air, and when the piston on the piston-rod 26 is allowed to be forced inwardly by the spring 27 the rod 6 will push the arm 2 into the position shown in full lines in Fig. 3, thereby starting the compression of air.

The operation is as follows: The gear-wheels 4 and 5 being in engagement when the car is started the crank-axle will be revolved and will start the air-compressors to compressing air in the compressed-air-storage cylinder, when if the valve 42 be opened by the motor-man or brakeman air will be forced through the pipe 22 into the cylinder 23, forcing its piston outwardly and turning the lever 8 on its pivot, and by its intermediate connections with the brake-beams it will force them into engagement with the car-wheels, and thereby stop the car, and if air is compressed above a certain degree in the compressed-air cylinder the piston-rod 27 and its piston will be forced outwardly, contracting the spring 27, and by the intermediate connections of said piston-rod with the pivoted arm 2 said arm will be folded, thus drawing the cog-wheel thereon out of engagement with the cog-wheel on the car-axle and stopping the air compression.

It will thus be understood that when air is compressed to a certain degree in the compressed-air-storage cylinder if the valve 42 is opened the brakes will be set to stop the car and that when air is compressed above such degree in the compressed-air-storage cylinders the regulator will operate to disconnect the gear-wheels 4 and 5 and stop the compression of air therein.

I claim—

1. An air-brake for cars, comprising a gear on the car-axle, brake-beams, a compressed-air-storage cylinder, compression-cylinders communicating therewith for compressing air therein to operate the brake-beams, pistons therein, a crank-axle to which the pistons are connected, a gear on said axle adapted to be engaged and disengaged with the gear on the car-axle, a foldable arm in which the crank-axle is suspended from the car-body, and a regulating-cylinder communicating with the compressed-air-storage cylinder, a piston therein and connections between said piston

and foldable arm for folding and unfolding it to respectively disengage and engage the gear-wheels, substantially as described.

2. An air-brake for cars, comprising a gear on the car-axle, brake-beams, a compressed-air-storage cylinder, compression-cylinders communicating therewith for compressing air therein to operate the brake-beams, pistons therein, a crank-axle to which the pistons are connected, a gear on said axle adapted to be engaged and disengaged with the gear on the car-axle, a foldable arm in which the crank-axle is suspended from the car-body, a regulating-cylinder communicating with the compressed-air-storage cylinder, a piston therein and connections between said piston and foldable arm for folding and unfolding it to respectively disengage and engage the gear-wheels, substantially as described.

3. An air-brake for cars, comprising a gear on the car-axle, brake-beams, a compressed-air-storage cylinder, compression-cylinders communicating therewith for compressing air therein to operate the brake-beams, pistons therein, a crank-axle to which the pistons are connected, a gear on said axle adapted to be engaged and disengaged with the gear on the car-axle, a foldable arm for suspending said crank-axle, a regulating-cylinder communicating with the compressed-air-storage cylinder, a piston therein and connections between said piston and foldable arm, for folding and unfolding it to respectively disengage and engage the gears, a compression-cylinder communicating with the compressed-air-storage cylinder, a piston therein, and connections between said piston and the brake-beams, substantially as described.

4. An air-brake for cars, comprising a gear on the car-axle, brake-beams, a compressed-air-storage cylinder, compression-cylinders communicating therewith for compressing air therein to operate the brake-beams, pistons therein, a crank-axle to which the pistons are connected, a gear on said axle adapted to be engaged and disengaged with the gear on the car-axle, a foldable arm for suspending said crank-axle, a regulating-cylinder communicating with the compressed-air-storage cylinder, a piston therein, connections between said piston and foldable arm, for folding and unfolding it to respectively disengage and engage the gears, a compression-cylinder communicating with the compressed-air-storage cylinder, a piston therein, connections between said piston and the brake-beams, substantially as described.

5. An air-brake for cars, comprising a gear on the car-axle, brake-beams, a compressed-air-storage cylinder, compression-cylinders communicating therewith for compressing air therein to operate the brake-beams, pistons

therein, a crank-axle to which the pistons are connected, a gear on said axle adapted to be engaged and disengaged with the gear on the car-axle, a regulating-cylinder communicating with the compressed-air-storage cylinder, a piston therein, 5 a pivoted lever, connections between said lever and said piston and between said lever and the crank-axle for engaging and disengaging said gears, a compression-cylinder communicating with the compressed-air-storage cylinder, a piston therein, a pivoted lever to which said piston is connected, connections between said lever and the brake-beams and slidable connections 10 between said levers, substantially as described.

6. An air-brake for cars, comprising a gear on the car-axle, brake-beams, a compressed-air-storage cylinder, compression-cylinders communicating therewith for compressing air 15 therein to operate the brake-beams, pistons therein, a crank-axle to which the pistons are connected, a gear on said axle adapted to be

engaged with the gear on the car-axle, a regulating-cylinder communicating with the compressed-air-storage cylinder, a piston therein, 25 a pivoted lever, connections between said lever and said piston and between said lever and the crank-axle for engaging and disengaging said gears, a compressed-air-storage cylinder, a piston therein, a pivoted lever to 30 which said piston is connected, connections between said lever and the brake-beams, slidable connections between said levers, and means for controlling the feeding of air from the compressed-air-storage cylinder to the 35 last-mentioned compression-cylinder, substantially as described.

In testimony whereof I have signed my name in the presence of the subscribing witnesses.
